(57) **CLAIM**

The ornamental design for a speaker as shown and described.

DESCRIPTION

FIG. 1 is a top, front and left side perspective view of a speaker showing my new design;

FIG. 2 is a rear perspective view thereof;

FIG. 3 is another top, front and left side perspective view thereof;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof;

FIG. 10 is an enlarge view of a top left region in FIG. 3;

FIG. 11 is a cross-sectional view along a direction indicated by the arrow in FIG. 6; and,

FIG. 12 is another top, front and left side perspective view thereof, shown in an alternate environment of use.

All of the broken lines illustrate unclaimed features that do not form a part of any of the embodiments, and the broken lines form no part of the claimed design.
